UNITED STATES PATENT OFFICE.

OWEN G. CATES, JR., OF ST. LOUIS, MISSOURI.

FASTENER FOR MEETING-RAILS OF SASHES.

SPECIFICATION forming part of Letters Patent No. 536,602, dated April 2, 1895.

Application filed September 17, 1894. Serial No. 523,244. (No model.)

To all whom it may concern:

Be it known that I, OWEN G. CATES, Jr., a citizen of the United States, residing in the city of St. Louis, State of Missouri, have invented a certain new and useful Improvement in Sash-Fasteners, of which the following is a full, clear, and exact description, reference being had to the accompanying drawings, forming a part of this specification, wherein—

10 Figure 1 is a sectional view of my improved fastener in operative position on the upper and lower sashes. Fig. 2 is a similar view, showing a modified form of key for operating the dog or catch. Fig. 3 is a detailed view 15 of the upper sash-section of the fastener. Fig. 4 is a similar view of the lower sash-section of the fastener; and Fig. 5 is a cross-sectional view of the lower sash-section, as taken on line 5—5, Fig. 2.

20 This invention relates to a new and useful improvement in sash-fasteners, and consists in the peculiar construction, arrangement, and combination of the several parts comprising my improved fastener, as will be hereinafter described and claimed.

In the drawings, A indicates what I term the male section of the fastener, which is secured to the upper edge of the meeting rail of the upper sash A''. This member of the 30 fastener is in the form of a shell, and is provided with a slot or opening in its face, through which projects the tongue portion of a dog B, pivoted therein, said tongue being reduced at its sides, forming stops, which contact with the edges of the slot and limit the 35 outward movement of the dog, but permitting a free inward movement thereof.

C is a spring located within the shell, whose tendency is to hold the dog in its projected 40 position.

A' are suitable flanges by which the section A is secured to the meeting rail of the upper sash.

The other member, D, of the fastener, which 45 I term the female section, consists of a shell D, which is provided with suitable flanges by which it may be secured to the upper face of the meeting rail of the lower sash D''. This shell D is open at its bottom, and projects be-

yond the inner edge of the meeting rail, so as 50 to include and inclose the male section A, when both sashes are closed, as shown in Figs. 1 and 2.

E indicates a curtain-wall or partition, which divides the shell D vertically, said partition being about on the same vertical plane as the inner side face of the meeting rail. This wall E is formed with an opening e in its lower edge, while on each side of said opening are teeth or projections F. Shell D is provided with an opening or slot d in one of its end walls, through which a key or other device may be introduced to disengage the dog B from the teeth F, when the parts are in a locked position, as shown in Fig. 1. When 65 the dog is thus disengaged, either of the sashes may be raised or lowered as the case may be.

In Fig. 2, I have shown a trigger pivoted in the section D, which, by depressing the projecting handle, will be forced in, disengaging 70 the dog from the ratchet-teeth during the operation of raising the lower sash or lowering the upper one.

It will be noted that the dog in the male section is always in readiness to engage the 75 teeth in the female section, whenever the sashes are brought in such relation to each other that the parts can co-operate.

Having thus described my invention, what I claim, and desire to secure by Letters Patent, is—

1. In a sash-fastener, the combination with the male section in the form of a shell, which is adapted to be secured to the meeting rail of the upper sash, of a dog pivoted therein, a 85 spring for holding the dog in a projected position, a female section in the form of a shell which is adapted to be secured to the meeting rail of the lower sash, a toothed portion in said female member with which the dog engages when the parts are in operative position, and a key for disengaging the dog from the teeth, substantially as described.

2. In a sash-fastener, the combination with a male section in the form of a shell, and having an opening in its face, of a dog pivoted in said shell, the tongue of which dog projects through the opening, a spring for holding the 95

dog in a projected position, a female section in the form of a shell, a partition wall in said female section having an opening in its lower edge, teeth on each side of said opening, with 5 which the dog in the male section is adapted to co-operate, and a key for disengaging the dog from the teeth, substantially as described.

In testimony whereof I hereunto affix my signature in presence of two witnesses, this 8th day of September, 1894.

OWEN G. CATES, JR.
